(57) CLAIM

The ornamental design for a sports game, as shown and described.

DESCRIPTION

FIG. 1 is a perspective view of the sports game;
FIG. 2 is a back view of the sports game;
FIG. 3 is a front view of the sports game;
FIG. 4 is a left side view of the sports game;
FIG. 5 is a right side view of the sports game;
FIG. 6 is a bottom view of the sports game;
FIG. 7 is a top view of the sports game; and,
FIG. 8 is a cross sectional view of the rim of the sports game.
The broken lines depict the portions of the sports game that form no part of the claimed design.
